UNITED STATES PATENT OFFICE

115,318

DESIGN FOR A POWER DRIVE UNIT FOR USE WITH HAND CUTTING TOOLS

Robert B. Pealer, Warren, Ohio, assignor to
Beaver Pipe Tools, Inc., Warren, Ohio, a cor-
poration of Ohio

Application April 25, 1939, Serial No. 84,554

Term of patent 14 years

To all whom it may concern:

Be it known that I, Robert B. Pealer, a citizen
of the United States of America, residing at War-
ren, in the county of Trumbull and State of Ohio,
have invented a new, original, and ornamental
Design for a Power Drive Unit for Use With Hand
Cutting Tools, of which the following is a speci-
fication, reference being had to the accompan-
ying drawing, forming part thereof.

In the drawing, Fig. 1 is a perspective view of

an end and one side of the power drive unit for
use with hand cutting tools, embodying my new
invention; Fig. 2 is a perspective view of the other
end and side thereof.

I claim:

The ornamental design for a power drive unit
for use with hand cutting tools, substantially
as shown.

ROBERT B. PEALER.
